[57] CLAIM

The ornamental design for an automotive body filler file, as shown and described.

DESCRIPTION

FIG. 1 is a top plan view of an automotive body filler file showing a first embodiment of my new design; FIG. 2 is a side elevational view thereof, the opposite side being a mirror image;

FIG. 3 is a left end elevational view thereof;

FIG. 4 is a right end elevational view thereof;

FIG. 5 is a bottom plan view thereof;

FIG. 6 is an end elevational view of the automotive body filler file showing an alternate embodiment of my new design, the top, sides and bottom views being substantially the same as FIGS. 1, 2 and 5 except for the curvature of the abrasive surface thereof;

FIG. 7 is an opposite end elevational view thereof.
